US00D409155S

United States Patent [19] Goleto

[11] Patent Number: Des. 409,155

[45] Date of Patent: ** May 4, 1999

[54] PROGRAMMABLE LOGIC CONTROLLER

[75] Inventor: **Andre Goleto**, Plascassier-Grasse, France[73] Assignee: **Schneider Automation**, Valbonne, France

[**] Term: 14 Years

[21] Appl. No.: 29/073,628

[22] Filed: Jun. 26, 1997

[30] Foreign Application Priority Data

Dec. 26, 1996 [FR] France 96 7352

[57] CLAIM

The ornamental design for a programmable logic controller, as shown and described.

DESCRIPTION

FIG. 1 is a top, front and right side perspective view of programmable logic controller showing my new design; and,

FIG. 2 is a top, front and left side perspective view thereof. The structure shown in phantom lines in FIGS. 1 and 2 is for illustrative purposes only and forms no part of the claim design.

1 Claim, 2 Drawing Sheets

FIG. 1

FIG. 2
